United States Patent Office

Des. 205,300
Patented July 19, 1966

205,300

COMBINED CANDLE HOLDER AND CANDLE THEREFOR

David Douglas, Manitowoc, Wis., assignor to East Wisconsin Trustee Company of Manitowoc, Manitowoc, Wis., a corporation of Wisconsin

Filed June 4, 1964, Ser. No. 80,283

Term of patent 14 years

(Cl. D48—2)

FIG. 3

FIG. 4

FIG. 1 is a side elevation view of the design of this invention;

FIG. 2 is a top plan view of the design shown in FIG. 1;

FIG. 3 is a top plan view similar to FIG. 2 but with the candle and mantle removed from the base portion; and

FIG. 4 is a sectional view taken on line 4—4 of FIG. 3.

I claim:

The ornamental design for a combined candle holder and candle therefor, substantially as shown and described.
